UNITED STATES PATENT OFFICE.

CLARENCE T. HOLT, OF MIDDLESEX BOROUGH, NEW JERSEY, ASSIGNOR TO BOUND-BROOK OIL-LESS BEARING COMPANY, OF BOUND BROOK, NEW JERSEY, A CORPORATION OF NEW JERSEY.

POSITIONING DEVICE FOR METAL-WORKING MACHINES.

1,293,096.

Specification of Letters Patent.

Patented Feb. 4, 1919.

Application filed March 14, 1917. Serial No. 154,648.

To all whom it may concern:

Be it known that I, CLARENCE T. HOLT, a citizen of the United States, and a resident of borough of Middlesex, in the county of Middlesex and State of New Jersey, have invented certain new and useful Improvements in Positioning Devices for Metal-Working Machines, of which the following is a full, clear, and exact description, where-
10 by any one skilled in the art may make and use the same.

The invention relates primarily to metal-
working machines, and is more particularly directed to a gaging or positioning device
15 which becomes a part of or is an attachment for a machine of this character.

Where an expanded mandrel is used to hold a tubular or cylindrical part during the operations of the main cutting tool and the cross-cut tools, it is primarily essential
20 that the part to be operated upon be exactly positioned with reference to the tools.

The device hereinafter defined is designed to insure a proper positioning and operation
25 of the tools.

It is the principal object of the invention to provide a stop device in conjunction with the head of the machine, its operating levers, and mandrel or face-plate to insure
30 definite positioning of the "stock" to be operated upon, whereby the tools of the main slide and tools of the cross slide will operate in definite manner upon the stock.

A further object of the invention is to apply such a gage or stop device in a manner which will insure, under manual or automatic uses of the machine, proper and definite positioning of the stock with reference to the cutters.
35

It is a further object to provide a stop device for positioning the stock that will be automatically removed by manipulation of the machine to bring forward the cutters for operation upon the stock.
40

With these objects and purposes in mind, the following is delineated showing a form and application of the invention.

Referring to the drawings:

Figure 1 is a plan view illustrating the
50 device.

Fig. 2 is a side elevation, with parts illustrated in Fig. 1.

Fig. 3 is a sectional view along the spindle with parts broken away.

Fig. 4 is a similar sectional view showing 55 the vertical position of the parts.

Fig. 5 is an exterior view of the expanding arbor.

Fig. 6 is an end and side view of the tip or 60 expansion member of the arbor.

Fig. 7 is a plan view of the sleeve and appurtenant parts.

An expanding mandrel for gripping a piece to be turned and trimmed is generally well-known in the art. The invention herein defined has to do with an expanding mandrel with features of attachment not heretofore used or known to applicant.
65

With the ordinary metal - working machine, an expanding mandrel may have been 70 employed for holding the stock or piece to be turned, but the stock has been applied to the mandrel without definitely locking it with reference to the main slide tools and cross-cut tools and their positions.
75

In the device under consideration, there is a definite stop which is actuated from the lever controlling the expanding mandrel and which upon a forward movement of the lever and collapse of the expanding mandrel 80 positions the stock and acts as a fixed abutment against which the stock or article to be operated upon may impinge.

Upon a reverse movement of the operating lever, the stop is effectively removed and is 85 naturally withdrawn from the path of the tools of the machine. This provides for clearance of all tools and, at the same time, gives a fixed and definite positioning for the stock with reference to the tools.
90

The stop is connected directly with the operating mechanism of the mandrel and appurtenant devices, and there is a definite assurance of coöperation between the parts which will give the necessary prescribed effect of operation of tools upon the stock.
95

The device is particularly advantageous where individual parts are to be turned and trimmed as to their ends inasmuch as, with a double tool upon the cross slide and ade- 100

quate tools upon the main slide, a cylindrical part may be positioned, turned as to its exterior, and trimmed as to its ends without necessitating any unusual amount of delicate positioning on the part of the operative. The part to be turned is merely slid on to the mandrel against the stop; the mandrel is expanded; and it is then in position to be accurately turned and trimmed by the tools.

10 In the accompanying drawings, the device is shown in connection with a lathe which has various details which in no way affect the operation of the stop device more than would be the case in any form of lathe.

15 The particular form of device shown is merely illustrative, in conjunction with the stop and its direct coöperation and co-action with the tools, of a metal-working machine.

Referring to said drawings, the numeral 20 1, denotes a frame-work which carries the usual slide blocks 2, for the main cutting tool 3, and the cross slide block 4, for the cross-cut tools 5. It, of course, also bears the spindle 6, which, through suitable gears 25 is connected with the driving mechanism for the spindle and is provided with chucking devices, etc.

As illustrated in the drawings, the spindle 6, has a longitudinal movement induced 30 by a collet 7, through the connection of a hand-lever 8, pivoted to the frame through a lathe 9, and adapted to advance or retract the spindle or the parts mounted upon and connected therewith.

35 The spindle 6, is driven through suitable gearing and a gear 10, or other suitable driving connections and may operate as a chucking spindle in the ordinary method of such machines. In Figs. 1 and 2, a chucking device 11, is illustrated merely to define the type of machine.

Ordinarily, in practice, the chucking device 11, operates the feed tube of the spindle, and is provided with an adjustable stop 12, 45 which determines the action thereof of rearward movement of the lever 8.

All of these parts are well-known in the art. In the present instance, instead of utilizing a chuck such as is commonly employed, 50 an expanding mandrel 13, is used in connection with the face-plate 14, or other attachment of the spindle.

This expanding mandrel is actuated by longitudinal movement of the spindle or 55 ordinary feeding tube through the manipulation of the lever 8, and coöperates with the stop mechanism hereinafter defined.

The expanding mandrel consists of a tapered tail-piece 15, which fits the face-plate 60 14, or other element, and has an extended shank 16, terminating in a tapered head 17. Over this tapered head is fitted an expandible member 18, which forms the direct arbor upon which the "work" is to be located. 65 The above parts have a central bore through

which passes a spindle 19, which impinges on its outer end through a collar 20, and adjusting nuts 21, against the expanding part 18. The spindle 19, is connected with the reciprocating and rotary spindle 6, and it is obvious that upon a movement of the spindle 19, the expandible member 18, will be moved relatively to the tapered head piece 17, and will therefore be expanded to hold the "stock" or "work" or will be moved 75 to release said "stock" or "work" dependent upon the movement of the operating lever 8, which moves the main spindle or sleeve 6.

X indicates a piece of work or tubular member which must be finished as to its exterior by the main tool 3, and must be trimmed as to its ends by the cross-cut tools 5.

With the above, general delineation, the essence of the invention may be defined as 85 consisting of a stop mechanism coöperating with the expanding mandrel; definitely locating the "work" or the stock piece X, where the main tool 3, will perform its function with a minimum of movement; and 90 the cross tools 5, will always operate upon the "stock" without necessity of accurate location other than that of forcing the "stock" against the stop.

Connected with the collet 7, and moved 95 thereby is a sliding sleeve 22, which sleeve slides upon a pin 23, fixed to the machine base or casing. This member 22, is connected through the collet and its connections with the lever 8, so that it is moved 100 when said lever is moved. The sleeve has a boss 24, through which extends a stop-bar 25. Said bar is made adjustable in said boss and may be locked by nuts 26, 27.

The bar extends through bearings 28, 29, 105 formed on the gear-housing or other convenient part of the machine so that it may have a direct, reciprocating motion when the lever 8, is moved.

The forward end of the stop-bar 25, extends downwardly as at 30, and has an enlarged end 31, to serve as a stop and abutment to locate the article which is being placed upon the mandrel.

It will be understood that the stop-bar 25, 115 is moved by the lever 8, which, of course, actuates the spindle, feed tube, or similar device and in turn actuates the expanding mandrel 13.

In operating the device, the cross slide 4, 120 with its tools 5, is located along the slide-bed in a definite position to perform a transverse operation and cut upon the "stock." With the tools backed off and with the main cutting tool 3, at one limit of its play, 125 the lever 8, is thrown forward to release the expanding mandrel. This movement of the lever throws the stop-bar 25, forward until its head 31, is in exact position to aline the stock with the cross-cut tools 5. The 130

stock is then placed over the mandrel and forced against the fixed stop. The lever 8, is then thrown backward, expanding the mandrel to hold the stock in defined position 5 with reference to the cross-cut tools 5. This operation locks the stock upon the mandrel in definite position with reference to the tools. The main tool 3, and the cross-cut tools may now be advanced simultaneously 10 and, of course, in the meantime the fixed stop has been retracted by the movement of the lever 8, so that the tools have a clear field for operation.

As soon as the operation of the tools has 15 been completed, the lever 8, is thrown forward carrying with it the fixed stop ready to receive another piece, and the finished piece of "stock" or "work" may be removed.

The advantages of the device will be apparent inasmuch as the stop, co-acting and moving with the lever simultaneously with the operation of the expanding mandrel, permits the locating of the "work" or "stock" in definite position where the tools 25 will require no special adjustment with reference to the "stock". The speed of handling and operating such a machine is materially increased; and in place of having skilled labor, ordinarily required, for locking the "work" upon the spindle or mandrel, entirely unskilled labor may be employed.

After the tools are once adjusted in the slides and the slides are set between their 35 ordinary stops, it is only necessary to throw forward the lever; place a piece of stock on the expanding mandrel and against the stop; throw back the lever and advance the tools.

40 Of course, it is quite obvious that the device as illustrated shows a hand-operated lathe. There is, of course, no reason why the same stop device might not be equally well applied to an automatic machine. It involves in the main the advancement and retraction of a fixed stop for definitely locking a "stock" or "work" with reference to the cutting tools for performing a complete 45 series of operations both as to exterior finish and end finish and sizing of the "stock". Obviously, the exact details of the mechanism might be modified and varied to suit the exigencies of any particular case so long as the stop locates the stock definitely upon 50 the spindle during the movement of the actuating mechanism for said spindle.

What I claim as my invention and desire to secure by Letters Patent is:

1. In a device for positioning and finishing 60 tubular pieces, the combination of a spindle, an expanding mandrel coöperating with said spindle for interiorly holding and releasing the tubular pieces, a stop device, and connections intermediate the stop device 65 and the spindle, whereby the tubular piece is

definitely located upon and clutched by said spindle with its periphery and ends accessible to cutting tools.

2. A positioning device consisting of an adjustable stop connected with the spindle 70 operating mechanism of a metal-working machine and adapted to engage a tubular piece of work, means for actuating the spindle mechanism including an expanding mandrel, means for moving said stop in predetermined relation with reference to the control of the spindle and expanding mandrel whereby the tubular piece is definitely located upon the mandrel with reference to the cutting tools, and cutting tools operating 75 upon the periphery and ends of the tubular piece.

3. In a device of the character described, a spindle, an expanding mandrel rotated thereby, means for opening and closing said 80 expanding mandrel, a reciprocating stop actuated by said means for locating a tubular piece of work upon the expanding mandrel, and cutting tools positioned to operate upon the periphery and ends of the tubular 85 piece.

4. In a device of the character described, a spindle, a lever for actuating said spindle, an expanding mandrel rotated by the spindle and expanded and contracted by the operating lever, a reciprocating stop sliding with said actuating means and spindle for positioning a tubular piece upon the expanding mandrel, and cutting tools positioned to finish the entire exterior of the 90 tubular piece.

5. In a device of the character described, a spindle, a lever for actuating said spindle, an expanding mandrel rotated by the spindle and expanded and contracted by the 105 operating lever, an adjustable reciprocating stop sliding with said actuating means and spindle for positioning a tubular piece upon the expanding mandrel, and cross-cutting tools positioned to operate upon the ends of 110 said tubular piece and a side-tool for trimming said piece longitudinally.

6. In a device of the character described, a rotary spindle, a lever for reciprocating said spindle, an expanding mandrel expanded and contracted by the reciprocations of the spindle, a lever for moving said spindle to actuate the expanding mandrel, a reciprocating stop connected with said spindle and lever, said stop forming an abutment for positioning a tubular piece upon the mandrel when said mandrel is contracted, and cutting tools definitely located to engage said tubular piece when positioned against the stop.

7. In a device of the character described, a rotating reciprocating spindle; an expanding mandrel connected therewith, adapted to be rotated with said spindle and actuated in its expanding and contractile action by the 130

reciprocations thereof; a lever for actuating said spindle, a sliding stop actuated with said lever and spindle and forming a fixed abutment for a tubular piece as it is applied to the expanding mandrel, said stop moving away from the tubular piece upon expansion of the mandrel, and cutting tools operating upon said tubular piece to finish its ends simultaneously.

5

to the expanding mandrel, said stop moving away from the tubular piece upon expansion of the mandrel, and cutting tools oper-

CLARENCE T. HOLT.
